UNITED STATES PATENT OFFICE.

ALBERT EDWARD ALLEN, OF REDLANDS, CALIFORNIA.

MAP-CASE.

1,329,875.

Specification of Letters Patent.

Patented Feb. 3, 1920.

Application filed June 11, 1919. Serial No. 303,420.

To all whom it may concern:

Be it known that I, ALBERT EDWARD ALLEN, a citizen of the United States, and a resident of Redlands, in the county of San Bernardino and State of California, have invented certain new and useful Improvements in Map-Cases, of which the following is a specification.

My invention is an improvement in map cases, and has for its object to provide a case of the character specified, especially adapted for holding and displaying maps wherein a folding table is provided, having at each side a case, a roller being journaled in each case for supporting the map, and the map being arranged to be moved over the table when unfolded.

In the drawings:

Figure 1 is a perspective view of the case folded;

Fig. 2 is a similar view with the case unfolded;

Figs. 3, 4 and 5 are sections on the lines 3—3, 4—4 and 5—5, respectively, of Fig. 2.

In the present embodiment of the invention, a table is provided, consisting of similar sections 1, and they are hinged together, as indicated at 2, to fold into superposed position, as shown in Fig. 1, or to fold into the same plane, as shown in Fig. 2. A case 4 is secured to each section at the outer edge thereof, each of the cases being of rectangular cross section and of a length corresponding to the length of the table section.

A reel or roller 5 is journaled in each case longitudinally thereof, and each roller has an extended journal pin 6 which extends through the end of the case, and the end of the journal pin is squared, as shown, to receive a crank 8. The map 9 winds upon the rollers at its ends, and each table section is slotted at its outer edge and at the case, as indicated at 10, to permit the map to pass out from the case on to the table. Each case has rounded feet 11 at its ends forming the support when the table is unfolded into the map displaying position.

Means is provided for holding the sections in alinement, the said means comprising a bolt 12 which is mounted to slide in alining bearings 13 on the under side of the table section, and a plate spring 14 is arranged above each bolt to press the bolt downward when the table is unfolded.

Each bolt has a rabbeted portion 15 at one end for engaging one of the bearings 13 to lock the bolt in operative position. These bearings 13 and the hinges 2 are carried by metal strips 16 which provide reinforcing means for the ends of the table sections. A brake is provided for each roller at each end thereof. Each brake consists of a bar 17 which is pivoted at 18 within the case, and which engages the adjacent journal pin, as shown in Fig. 4. Each bar 18 has a lug 19 on the opposite side of the journal pin from the pivotal connection, and each bar at its free end is engaged by a screw 20 for pressing the bar into engagement with the journal pin. Each of the screws 20 is threaded through a block 21 mounted at the adjacent end of the slot 10, and each block has its upper end recessed as shown at 22 to receive the square head of the screw. The head of the screw is thus below the level of the top of the table when extended, but access may be had thereto for turning the screw to secure the proper amount of tension on the adjacent roller.

When folded, the map case occupies the position of Fig. 1, the table sections being superposed on each other, with the cases at the outer sides of the section. A handle 23 is connected with one of the sections for convenience in carrying the case, and suitable means may be provided for holding the table sections in the position of Fig. 1. The weight of the sections, however, is sufficient for this purpose.

When the map is not in use, the case is folded in the position of Fig. 1 and can be easily transported from place to place. When it is desired to use the map or other article held by the case, the table sections are unfolded, as shown in Figs. 2 and 3, and the bolts 12 are shoved through the alining bearings 13 until the shoulder formed by the rabbet 15 engages the bearing as shown in Fig. 5. The spring 14 holds the bolt in this position, although it may be easily disengaged by pressing the same upward. The case is placed on a suitable support, as, for instance, a table, and by means of the crank the map may be moved from roller to roller, displaying every part thereof, the body of the map passing across the extended table. The brake bars 17 are adjusted to give the proper tension, so that while the map moves

freely the rollers do not over-unwind, and when used in the wind they are locked tight to hold the map snugly to the table.

I claim:

5. 1. A device of the character specified, comprising similar table sections hinged together at one edge to fold in superposed position or into the same plane, means for locking the sections in the same plane, a case at the outer edge of each section and on the under side thereof when the table is unfolded, a roller journaled in each case, said rollers being adapted to carry a map winding upon the rollers at its ends, each section having a slot at the case for permitting the passage of the map, said rollers having at one end extended journal pins squared for engagement by a crank, and means for braking the movement of each roller, said 10 means comprising a brake bar engaging the journal pin, and means accessible from the top of the table for varying the pressure of the bar on the pin.
2. A device of the character specified, comprising similar table sections hinged together at one edge to fold in superposed position or into the same plane, means for locking the sections in the same plane, a case at the outer edge of each section and on the under side thereof when the table is unfolded, a roller journaled in each case, said rollers being adapted to carry a map winding upon the rollers at its ends, each section having a slot at the case for permitting the passage of the map, said rollers having at one end extended journal pins squared for engagement by a crank, and means for braking the movement of each roller.
3. A device of the character specified, comprising similar table sections hinged together at one edge to fold in superposed position or into the same plane, means for locking the sections in the same plane, a case at the outer edge of each section and on the under side thereof when the table is unfolded, a roller journaled in each case, said 15 20 25 30 35 40 45 50 55 60 65 70 75 80 85 90 95
4. A device of the character specified, comprising similar table sections hinged together at one edge to fold in superposed position or into the same plane, means for locking the sections in the same plane, a case at the outer edge of each section and on the under side thereof when the table is unfolded, a roller journaled in each case, said rollers being adapted to carry a map winding upon the rollers at its ends, each section having a slot at the case for permitting the passage of the map.
5. A device of the character specified comprising similar table sections hinged together at one edge to fold in superposed position or in the same plane, means for locking the sections in the same plane, a roller journaled at the outer edge of each section and longitudinally of the said edge, said rollers being adapted to carry a map winding upon the rollers at its ends, and a covering case for each roller.
6. A device of the character specified comprising similar table sections hinged together at one edge to fold in superposed position or in the same plane, means for locking the sections in the same plane, and a roller journaled at the outer edge of each section and longitudinally of the said edge, said rollers being adapted to carry a map winding upon the rollers at its ends.
7. A device of the character specified comprising similar table sections hinged together at one edge to fold in superposed position or in the same plane, and a roller journaled at the outer edge of each section and longitudinally of the said edge, said rollers being adapted to carry a map winding upon the rollers at its ends.

ALBERT EDWARD ALLEN.
